UNITED STATES PATENT OFFICE.

ARTHUR ROSENTHAL AND MARTIN ROSENTHAL, OF GRAND RAPIDS, MICHIGAN, AS-
SIGNORS TO ROSE PATCH AND LABEL CO., OF GRAND RAPIDS, MICHIGAN.

PRINTED LABEL AND PROCESS OR METHOD OF MANUFACTURING THE SAME.

Application filed September 25, 1926. Serial No. 137,705.

The objects of the invention are:

First, to provide a fabric label with the printing thoroughly impregnated and incorporated with the fabric without blurring.

Second, to provide an improved process of producing such a label generally and also of producing such a printed fabric label.

Third, to provide such a label that is protected until used.

10 Objects pertaining to details and economies of the invention will definitely appear from the detailed description to follow. The invention is clearly defined and pointed out in the claims.

15 Means which are our preferred embodiment are clearly illustrated in the accompanying drawing forming a part of this application, in which:

20 Fig. 1 is a diagrammatic elevation view of the machinery made use of in carrying out our improved process and producing our improved labels.

25 Fig. 2 is an enlarged detail view of a label strip showing the first step of the printing process and the printing taken from the intaglio plate.

Fig. 3 is a similar view of the second step, showing a complete printing of the label.

30 Fig. 4 is a detail view of the back side of the label strip showing the penetration of the ink.

Fig. 5 is a detail view of the glazed tissue paper overlay strip.

35 Fig. 6 is an enlarged detail view of a complete label in its fully folded and creased condition with the glazed tissue protector.

40 Referring to the drawing, 1 is the base frame of an intaglio printing press, shown in diagrammatic form. 2 is the bed carrying the intaglio plates 3 and 4. 5 is the counter supported in suitable guides 6. 7 is the label strip reel from which the label strip 8 is delivered to the printing press. 8 is the label strip, which may be either a 45 selvedge edge tape or a strip with folded edges, a strip with folded edges being illustrated particularly in Fig. 4. 9 is the guide for the label strip. 10 is the reel for the blotter strip. 11 is the blotter strip which 50 is delivered into the guide 9 back of the label strip 8. 12 is the blotter strip feed reel, operated by suitable ratchet which pulls the blotter strip at a different rate of speed from the advance of the label strip so as to economize on the amount of blotter used. 13 is

the overlay strip reel and 14 is the overlay strip of glazed tissue paper. 15 is the guide for the overlay strip and 16 is the guide for the label strip and overlay strip together, the overlay strip being delivered beneath the label strip after the printed label strip passes from the printing press. 60

17 are the label feed clamp jaws for grasping the printed label strip and overlay strip together and passing them beyond the cut-off shears 18. This serves to advance the label strip and cuts the same so it can be delivered to the label folder. 19 are the label delivery jaws shown in position grasping a label in the label folder ready to convey 70 it to the dotted position indicated in the packing chute. 65

20 are the movable folder and creaser members. 21 is the stationary folder and creaser member containing the heaters, here 75 shown as electric elements 22, 22. The broad upper member of jaws 17 carries the label into position over the stationary heating and folding member 21 and then the folder and creaser members are actuated to wrap and fold the ends of the label upwardly around the edges of the jaw. The jaw is then withdrawn and the folders complete the crease. This is described in detail in Patent No. 1,262,986 issued April 16, 1918. 80 to Arthur Rosenthal. 23 is the chute for the folded labels to deliver them to the packer underneath. 24 is the packer plunger head and 25 is the plunger rod, arranged to cooperate with the feed jaws and deliver the 90 labels into the chute. 85

This mechanism is all shown diagrammatically here but it is completely illustrated and its operation is described in our Patent No. 1,656,391, issued January 17, 95 1928, to which reference is made for a complete understanding of the details of the mechanism by which the various devices are actuated, that being no part of the present invention. 100

The label strip 8 is delivered to the printing press and is grasped by the feed and folder jaws 17. The blotter strip 11 is back of it and a printing operation occurs, the imprint of which is indicated in Fig. 105 2, that of the plate 3 being indicated at 3' and of the plate 4 being indicated at 4'. The blotter is then advanced and the feed jaws operate and advance the label strip a label length, when a second printing occurs 110

and the imprint 4' is superposed on the imprint 3', producing the completed label as indicated in Fig. 3. The imprint of the label shows complete at 26. Fig. 4 shows 5 the reverse of the same at 27, showing how the ink is forced through the fabric.

The label strip is advanced step by step and of course the ink has a slight opportunity to set when it passes from the printing 10 press to the guide 16. At this point the overlay strip is exactly positioned by the guide 16 and is passed very gently in contact with the printed label until it reaches the clamp and creaser jaws 17 where the parts 15 are shut close together and advanced as a single piece beyond the shears and cut off and passed to the creaser and folder.

The creaser and folder is heated here 20 electrically and the heat is of such intensity as to thoroughly iron and crease the label and also the overlay strip, which is of 25 glazed tissue paper. The heat is such that the crease is made permanent and the overlay strip is held permanently in place by its close contact and, due to the action of the 30 heater folding the same over the ends of the label, conforms thereto and remains in position on the finished label. The heat completes the incorporation of the ink with 35 the fabric, the overlay strip completely protects the same, and where the label strip has a seamed edge the labels when packed together serve as guards for each other, and they have opportunity to completely cure 40 before they are passed to a stitching machine.

We have illustrated electric heater means. 45 We have used gas and believe other means of heating might be utilized. We have illustrated in our disclosure double plate intaglio but desire to state that where three- 50 color work is done three plates might be used, and it is, of course, possible to deliver a plurality of labels side by side. We have 55 not deemed it necessary to illustrate such in this behalf.

We desire to claim this method of making the labels and also the label as thus produced.

Having thus described our invention what 50 we claim as new and desire to secure by Letters Patent is:

1. The method of making a printed label consisting in printing the same on double plate intaglio press with a blotter strip between the counter and the label strip, advancing the strip a label length and the blotter strip at a different rate for the second impression to complete the label, 55 delivering the label strip to a label cutter 60 in a continuous strip, applying an overlay strip of glazed tissue paper beneath the printed label strip, clamping the same to the label strip and cutting and then folding, and creasing the label and strip under heat, 65 as specified.

2. The method of making a printed label consisting in printing the same on intaglio press with a blotter strip between the counter and the label strip, advancing the strip a 70 label length and the blotter strip at a different rate, delivering the label strip to a label cutter in a continuous strip, applying an overlay strip of glazed tissue paper beneath the printed label strip, clamping 75 the same to the label strip and cutting and then folding, and creasing the label and strip under heat, as specified.

3. The method of making a printed label consisting in printing the same on double 80 plate intaglio press with the blotter strip between the counter and the label strip, advancing the strip a label length and the blotter strip at a different rate for the second impression to complete the label, delivering 85 the label strip to a label cutter in a continuous strip, clamping the same to the label strip and cutting and then folding, and creasing the label and strip under heat, as 90 specified.

4. An intaglio printed label with creased and folded ends, and an overlay strip of glazed paper folded at the ends to retain it in position thereon, as specified.

In witness whereof we have hereunto set 95 our hand.

ARTHUR ROSENTHAL.
MARTIN ROSENTHAL.
